(57) **CLAIM**

The ornamental design for an operator panel for inverter controller for electric motors, as shown and described.

DESCRIPTION

FIG. 1 is a front view of an embodiment of an operator panel for operator panel for inverter controller for electric motors, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a front and left side perspective view thereof.

The broken line showing of the operator panel is for illustrative purpose only and forms no part of the claimed design.
